STICK FILE

James H. Milling, Dallas, Tex.

Application March 2, 1939, Serial No. 259,439

6 Claims. (Cl. 129—23)

This invention relates to an improved file for papers, tickets and the like and includes an improved guard for the pointed end of the pin or spike so constructed that it will automatically move to a position to enclose and protect the pointed end of the spike.

It is a primary object of this invention to provide an improved file of simple construction which will be economical to manufacture and which will be durable and efficient in use enabling papers to be readily applied to or removed from the file, and provided with an improved guard that will function automatically to enclose the pointed end of the file after papers have been applied or removed therefrom to prevent accidental removal of papers or accidental injury through contact with the pointed end of the spike or pin.

More particularly, it is an aim of this invention to provide an improved pendulum type guard having means for pivotally mounting it whereby it may be swung in one direction away from the pin or spike, means in the free end thereof to normally receive and enclose the pointed end of the spike, means whereby the oscillating motion of the pendulum will be such that when released it will automatically swing back into a position to enclose said pointed end.

Still a further aim of the invention is to provide means of simple construction for mounting the pendulum including a rest whereby the pendulum may be held in a retracted position out of engagement with the pin, if desired.

Other objects and advantages of the invention will hereinafter become more fully apparent from the following description of the drawing, which illustrates a preferred embodiment thereof, and wherein:

Figure 1 is a front elevational view of one embodiment of the invention,

Figure 2 is a side elevational view, partly in section, of the same,

Figure 3 is a horizontal sectional view taken along the line 3—3 of Figure 1, and

Figure 4 is a side elevational view of another embodiment of the invention.

Referring more particularly to the drawing, wherein like reference characters designate like or corresponding parts throughout the different views, 10 designates generally a base plate which is adapted to be rested on any suitable horizontal supporting surface such as a desk or a table. Projecting upwardly from the base 10 adjacent one end thereof is a spike 11 which is provided with a pointed free end 12. A rod 13 projects upwardly from the base 10 adjacent its opposite end and includes a standard portion 14 which is disposed substantially parallel to the spike 11 and which terminates at its upper end in a horizontally disposed shoulder 15 which pro-

jects away from the spike 11 and which in turn terminates in the arm 16 which is disposed obliquely to the standard 14 and shoulder 15, and which terminates in an eyelet or loop 17 disposed above and spaced from the pointed end 12. Portions 14, 15, 16 and 17 are all preferably formed integral, as best illustrated in Figure 2.

A pendulum type guard member, designated generally 18, is provided at one end with the spaced longitudinal slots 19 and 20 forming a transverse bar 21 therebetween which extends through the eyelet or loop 17 for pivotally mounting the guard 18 thereon. Slot 20, which preferably opens outwardly of the upper end of the guard 18 forms the ears 22 which are disposed on either side of the upper portion of the eyelet 17. Guard 18 is preferably enlarged at its lower free end to form the weighted portion 23 provided with a recess 24 which opens outwardly of the front side and bottom thereof and which is disposed in a vertical plane with the slots 19 and 20 so that when the guard 18 is in its normal depending position the pointed end 12 will be disposed within the recess 24, as best seen in Figure 2.

Guard 18 is preferably flat and relatively wide and tapers in width toward its upper end so that the portion 25, between the weighted portion 23 and the lower end of the slot 19 may be used for advertising matter or may be provided with a mirror.

From the foregoing it will be seen that the spike or pin 11 is adapted to hold papers, tickets, or the like which may be applied to or removed from its pointed end 12 by manually moving the guard 18 on its pivot 17 toward the arm 16. As soon as the papers or tickets have been applied to or removed from the pin 11 the guard 18 is released and it will swing back to its position, as seen in Figure 2. The sides of the slot 19 and the ears 22 prevent the guard 18 from swinging laterally so that when it is oscillated it will always swing directly toward the arm 16 or the pin 11 to direct the recess 24 toward the pointed end 12 due to the fact that the loop or eyelet 17 is disposed in a plane with the arm 16, and as the eyelet 17 is directly above the pin 11, the guard 18 when in its normal depending position will be disposed so that the pointed end 12 is positioned in the inner or back part of the recess 24. As seen in Figure 2, the thickness of bar 21 is substantially less than the diameter of eyelet 17 and the length of slots 19 and 20 is substantially greater than the thickness of the rod 13 so that guard 18 may be raised relatively to eyelet 17 and when raised and retracted may be positioned so that the recess 24 is resting on the shoulder 15, as illustrated in dotted lines in Figure 2, to be thereby held in a retracted position. This may be done where it is desirable to apply or

remove a number of papers or tickets and where it is more convenient to have the pointed end exposed while such operation is being performed, after which guard 18 can be returned to its normal position by lifting it upwardly to release it from the shoulder 15 to allow it to swing automatically back to its full line position.

In Figure 4, another embodiment of the file is illustrated which is adapted to be hung from a hook secured to a vertical supporting surface, such as a wall, designated 26, in which is secured a hook 27. In this embodiment of the invention a base plate 10' is provided at one end with an opening 28 by means of which it is adapted to be removably suspended from the hook 27. A substantially U-shaped spike 11' is secured at one end to the base 10', adjacent its lower end, and is tapered at its opposite end to provide the point 12'. U-shaped member 11' at its secured end is provided with the horizontally disposed portion forming the shoulder 15' which is disposed in the same relative position to the pointed end 12' as the shoulder 15 is to the end 12. An arm 16' projects outwardly from the plate 10', adjacent its upper end, and terminates in a loop or eyelet 17' disposed above and spaced from the pointed end 12' to receive the bar 21' of the pendulum guard 18' which corresponds in construction to the guard 18.

The operation of the stick file, as illustrated in Figure 4, is identical with the operation of the file as illustrated in Figures 1 and 2 with the pendulum guard 18' being swung inwardly toward the base plate 10' to expose the point 12' and being constructed so that it can be raised relatively to the eyelet 17' for resting the recessed portion 24' of the weighted portion 23' on the shoulder 15', when in a fully retracted position. A further description of the operation of the file, illustrated in Figure 4, is therefore considered unnecessary.

Various modifications and changes in the precise construction and arrangement of the parts forming the invention are contemplated and may obviously be resorted to and the right is therefore expressly reserved to make such variations and changes as do not depart from the spirit and scope of the invention as hereinafter defined by the appended claims.

I claim as my invention:

1. A device of the class described comprising an upwardly projecting pin, a standard spaced from said pin and having its upper end bent to provide an arm projecting toward said pin, said arm terminating in a loop disposed above and spaced from the upper end of said pin, a plate having spaced longitudinal slots at one end thereof, one of said slots opening outwardly of an end of the plate, said slots loosely engaging remote portions of said loop for pivotally mounting said plate thereon, and said plate being provided with an enlarged opposite end having a recess in one side thereof to receive the upper end of said pin when the plate is in its normal depending position.

2. A stick file comprising a base, a pin secured to said base and having its free end projecting upwardly, an arm secured to and projecting from said base and terminating in a loop disposed above and spaced from the free end of said pin, and a guard member having spaced slots at one end thereof forming a transverse bar therebetween for loosely engaging said loop to pivotally mount said member, the opposite end of said member being provided with a recess opening out-

wardly of one side and of the bottom thereof to receive the free end of said pin when in a normal depending position.

3. A stick file comprising a base member, a pin projecting upwardly therefrom and terminating in a pointed free end, a standard projecting upwardly from said base member in spaced apart relationship to said pin, said standard terminating in an obliquely disposed free end which terminates in an eyelet or loop disposed above and spaced from the pointed end of said pin, a guard member having spaced longitudinal slots at one end thereof forming a transverse bar for loosely engaging said eyelet to pivotally mount said member, said slots engaging the top and bottom portion of said eyelet for guiding the swinging movement of said guard member, the opposite end of said guard member being provided with a recess opening outwardly of one side thereof and disposed in a plane with said slots for receiving the pointed end of said pin when in a normal depending position.

4. A device as in claim 3, said standard having a horizontally disposed portion forming a rest to be engaged by the recess in the free end of said guard member for retaining said member in a retracted position out of engagement with the pin.

5. A stick file comprising a supporting member having an opening adjacent one end thereof adapted to engage a hook, a U-shaped member having one end secured to said supporting member and its free end terminating in a point, an arm secured to and projecting outwardly from said supporting member and terminating in an eyelet disposed above and spaced from said point, a pendulum having an opening adjacent one end thereof to receive the lower portion of said eyelet for pivotally mounting the pendulum thereon, spaced ears projecting upwardly from said end and on either side of the upper portion of said eyelet, the free end of said pendulum being provided with a recess opening outwardly and downwardly for receiving the pointed end of said U-shaped member, said pendulum being movable inwardly for exposing said pointed end and being guided by said ears, when moving toward said pointed end, for disposing said recess to receive said pointed end.

6. A stick file comprising a base, a pin projecting upwardly from said base, a rod secured to and projecting upwardly from said base including a standard spaced from said pin and an obliquely disposed arm, a horizontally disposed shoulder at the junction of said standard and arm, an eyelet at the free end of said arm disposed above and spaced from the free end of said pin, and a pendulum having longitudinally disposed spaced slots at one end thereof forming a transverse bar therebetween for loosely engaging said eyelet to pivotally mount the pendulum, and the opposite end of said pendulum being enlarged and weighted and provided with a recess opening outwardly of the front and bottom thereof to receive the free end of the pin when in a normal depending position, said slots being of sufficient length to permit the raising of said pendulum relatively to said arm for resting its recess on said shoulder for retaining it in a retracted position, said slots guiding the oscillating movement of the pendulum whereby the recess in the free end thereof will be directed toward the pointed end of the pin.
